Attorneys

UNITED STATES PATENT OFFICE.

CHARLES A. MOORE, OF ST. PAUL, MINNESOTA.

AIR-CONDITIONING APPLIANCE.

Application filed August 30, 1924. Serial No. 735,056.

My invention relates to improvements in air conditioning appliances and has for an object thereof to supply a simple, durable and efficient device adapted to ventilate a chamber, also to heat and wash the incoming freshening air and, further, to charge said freshening air with moisture.

With the foregoing and other objects in view, which will appear in the following description, the invention resides in the novel combination and arrangement of parts and in the details of construction hereinafter described and claimed.

In the drawing, the single view illustrates, in vertical section, a device embodying my invention, the same being shown as installed in a chamber.

Referring to the drawing, it will be observed that the structure formed by the floor 10, walls 11 and ceiling 12 encloses a chamber A. Within this chamber A is installed an appliance embodying my invention. Said appliance includes means for supplying fresh air to the chamber A in washed, 25 humidified and heated condition, also separate means providing for the egress of air from said chambers. Said latter means includes an upright duct B opening at the bottom thereof at a level near the floor 10 and opening at the top thereof at a level 30 near the ceiling 12. Dampers 13, 14 respectively fitted within the upper and lower ends of the duct B provide for regulating the egress of air from the chamber A through 35 said duct B and an outlet pipe 15 joining said duct B at a point between said dampers 13, 14, said pipe 15 being extended upward through the ceiling 12 into the outer air.

The means for introducing air to the chamber A includes an upright duct C comprising an upper portion c', preferably a metallic pipe, supported by legs 16, and a lower bell-like portion c² of fabric. Said lower duct portion c² comprises a split 45 holder-ring 17, a fabric top 18 apertured centrally thereof, and a fabric skirt 19 depending from the margin of the top 18, said top being bound at its margin to the ring 17. Said ring 17 provides for detachably securing said lower duct portion c² to said upper duct portion c', an internal annular groove 50 being formed at the lower margin of said latter duct portion to receive said ring. Located beneath the duct C and between the legs 16 is a pan 21 for water. The skirt 19, dipping into the water contained in the pan

21, is kept moist through absorption and supplies moisture to the absorbent top 18. An air ingress pipe 22 entering the chamber A through the wall 11 and the duct C 60 through the side of the upper duct section c' is provided within the duct C with two branches 23, 24 respectively fitted with dampers 25, 26, the branch 23 extending upwardly in the duct C and the branch 24 65 downwardly therein. Said latter branch 24, reaching through the central aperture in the top member 18, of the lower duct portion c², opens downward upon and close to the surface of the water in the pan 21. 70

Electrical heater elements 27 of conventional design are suitably secured inside of the upper duct portion c'.

In use, a damper 28 in the ingress pipe 22 and a damper 29 at the upper end of the 75 upper duct portion c' are opened more or less to regulate the ingress of air into the chamber A. So also is the upper damper 13 in the duct B, or the lower damper 14 therein, or both, opened to regulate the egress of 80 air from the chamber A as desired. With said dampers suitably adjusted and the heater elements 27 in operation, air is drawn through the ingress pipe 22 into the duct C where it is heated by the elements 27 and 85 buoyed upwardly and out of the duct portion c' into the chamber A at the ceiling thereof. Displaced by the incoming fresh air, the older air in the chamber A has egress therefrom through the duct B and 90 the pipe 15. Upon entry of the fresh air to the duct C through the pipe 22, the user, by manipulating the dampers 25, 26, can cause all of the incoming air to pass down the branch pipe 24, or cause all of said air 95 to pass up the branch pipe 23, or can divide the flow of said air through said two branch pipes 23, 24. The air fed upwardly into the upper duct portion c' is merely heated, which result may be desired when the outer 100 atmosphere contains a high percentage of humidity. The air fed downwardly in the duct C through the branch pipe 24 flows, first, against the surface of the water in the pan 21, thence passes upwardly brushing the 105 inner sides of the saturated skirt 19, and thence passes upwardly through the saturated top member 18, which comprises a screen-like diaphragm across the lower end of the duct portion c'. Washed and 110 charged with moisture by reason of its contact with the water in the pan 21 and with

the saturated skirt 19 and top member 18, the air, drawn upwardly by the action of the heater elements 27, is heated by said elements in its upward passage through the 5 duct portion c'.

In cleaning deposits of foreign matter from the skirt 19 and top member 18 the fabric structure formed thereby is removed from the duct portion c' by slightly collapsing 10 the split ring 17 and lowering it from its grooved seat in the duct portion c'. Being flexible, the skirt 19 readily permits of such removal of said air washing and moisture charging structure and, further, 15 without itself being removed, permits of the ready removal of the pan 21 for the purpose of cleansing the same of sediment.

Changes in the specific form of my invention as herein disclosed, may be made 20 within the scope of what is claimed without departing from the spirit of my invention.

Having described my invention, what I claim as new and desire to protect by Letters Patent is:

1. In an appliance of the class described, an upright duct, a diaphragm of fabric horizontally disposed and traversing the lower end of said duct, a skirt of fabric depending from the margin of said diaphragm, a bath in which said skirt dips, an ingress pipe leading into said duct and formed with two valved branches, one opening upwardly into the duct and the other 35 downwardly through the diaphragm and over the said bath, and means for inducing an upward flow of air in the duct.

2. In an appliance of the class described, an upright duct comprising a stationary 40 upper portion and a lower portion detacha-

ble from said upper portion and consisting of a bell-like structure of fabric, the top of said fabric structure forming a diaphragm at the lower end of said upper duct portion, an air ingress pipe leading into the upper portion of said duct and opening downward into said fabric structure through said diaphragm, a bath in which the skirt of said structure dips, and means within the upper duct portion for inducing an upward flow of air therein. 45

3. The combination with a structure forming a chamber, of an air ingress pipe and an upright duct comprising an upper pipe portion and a lower bell-like element 55 of fabric, said ingress pipe reaching inwardly through said upper pipe portion and extending downward through the top of said bell-like member, a bath in which the skirt of said bell-like member dips, and means 60 associated with the upper pipe portion of said duct for inducing an upward flow of air therein.

4. In an appliance of the class described, an upright duct, a diaphragm of fabric 65 horizontally disposed and traversing the lower end of said duct, a skirt of fabric depending from said diaphragm, a bath in which said skirt dips, an ingress pipe leading into said duct downwardly through 70 said diaphragm and opening over said bath, and means for inducing a flow of air downwardly in said ingress pipe, thence in a reverse turn over the surface of the bath, thence upwardly through the diaphragm 75 between pipe and duct and thence upwardly through said duct.

In testimony whereof, I have signed my name to this specification.

CHARLES A. MOORE.
